T. BODDE,
SUBMARINE SOUND DETECTOR,
APPLICATION FILED SEPT. 2, 1916.

1,371,728.

Patented Mar. 15, 1921.

UNITED STATES PATENT OFFICE.

THEODORE BODDE, OF LYNN, MASSACHUSETTS.

SUBMARINE-SOUND DETECTOR.

1,371,728.

Specification of Letters Patent. Patented Mar. 15, 1921.

Application filed September 2, 1916. Serial No. 118,184.

To all whom it may concern:

Be it known that I, THEODORE BODDE, a subject of the Queen of The Netherlands, residing at Lynn, in the county of Essex and State of Massachusetts, have invented certain new and useful Improvements in Submarine-Sound Detectors, of which the following is a specification.

This invention relates to submarine sound detectors, and has particular application to an apparatus for detecting sounds and tones emitted under the surface of the water, whether such sounds be purposely given, as in signaling, or are unintentionally produced, as by the propeller or other operating parts of a submarine vessel or torpedo.

In the present instance it is my purpose to provide a submarine sound detector which is exceedingly sensitive or responsive to sounds or tones, and which possesses a relatively wide range of action, so that any sounds or tones, whether weak or strong, or of different pitch, which are emitted under the water may be instantly detected even when produced at a relatively great distance from the vessel equipped with my apparatus.

Another object of the invention is to provide an apparatus of this character, embodying among other features, an element such as a wire or string which is adapted to be tuned to correspond with the frequency or periodicity of a sound or sounds emitted under the water, so that such sound or sounds may be instantly and readily detected, and in some instances their proximity or remoteness located.

With the above recited objects, and others of a similar nature in view, my invention consists in the construction, combination and arrangement of parts set forth in and falling within the scope of the appended claims.

In the accompanying drawings—

Figure 1 is a vertical cross-sectional view taken through a portion of the hull of a vessel and showing a preferred form of my sound-detector applied thereto, certain parts of the detector being shown in elevation and certain parts in section.

Fig. 2 is a similar view, but showing the

vibrating wire or string element of the apparatus as secured directly to the hull of the vessel instead of to a separate diaphragm.

Fig. 3 is a view, somewhat diagrammatically, of a further modified form of the invention and showing the employment of a microphone in circuit between the string or wire and the telephone receiver. 55

Fig. 4 is a similar view of another modification wherein the transverse force on the wire or string is exerted by a different magnetic device. 60

Fig. 5 is a similar view of still another modification in which the detector wire and the primary circuit of the telephone receiver 65 are in parallel in the battery circuit, with a choke coil in the latter.

Referring now to the accompanying drawings in detail, the letter A indicates conventionally a portion of the side of the hull 70 of a vessel, and which below the water line is provided with a relatively small bore or opening, a.

Surrounding this opening at the outside of the hull is a water-tight gasket 1, carrying a thin membrane 2, preferably of metal. To the center of this membrane, as at 3, is attached one end of a wire or string 4, which is preferably made of brass or phosphor-bronze, this wire somewhat resembling an 80 ordinary piano wire. Such wire is threaded through the bore, a, in the hull of the vessel and at its inner end is attached to a suitable sliding or reciprocating weight 5, which is shifted, or pulled by means of a coil spring 85

6, one end of which is connected to the weight as at 7, while the opposite end of the spring is connected as at 8 to a rectangular block 9 sliding in a correspondingly shaped bore 10 of the bearing 11. The weight 5 90 serves as an inertia means to limit the vibration of the wire to the wire itself. This sliding block 9 is provided with a longitudinally threaded bore 12, in which works the screw shaft 13, the outer end of this shaft 95 being journaled in the bearing 14, and such shaft is further provided with a worm-gear 15 meshing with the worm pinion 16 driven by a small electric motor, conventionally illustrated at M. When this motor M is 100

running, the rectangular sliding block 9 is moved or shifted slowly and periodically, for example during one-minute periods, toward or from the bearing 14 by means of the screw 13, driven by the motor through the intermediate train of gearing just recited, the movement of the block 9 toward or from the bearing 14 depending upon the direction of rotation of the motor shaft.

10 The rotation of the motor can be stopped at will, and is reversed periodically by a suitable automatic switching mechanism which is conventionally shown in Fig. 1, and is indicated as an entirety by the letter 15 S. In this connection it is to be understood that any switching mechanism known in the art, and adaptable to this purpose may be employed. For example, I have shown in Fig. 1 an adaptation of the switching mechanism shown in the U. S. patent to Louis, No. 777,116, dated December 13, 1904. It will be seen by reference to Fig. 1, that in adapting the Louis switch to my apparatus the arm h' is made rigid with the sliding block 9 and projects through the slot 11 in the bearing 11. The arms B' and B^2 support the guide rod b^2 and on this guide rod are two helical springs s and s' which are connected at the inner side of the lugs 30 or stops $f-f'$ mounted on the sliding or movable rod n which slides in the arms $B'-B^2$ and is connected at one end to the reversing switch K. The arm h' carries a slide piece h^2 and as the arm reciprocates 35 this slide piece at the ends of its strokes strikes the springs s and s' , compressing the latter and the resiliency of the springs being communicated to the sliding rod n , actuates the latter with rapidity to throw the 40 switch K, the direction of the throw of the switch of course depending upon which spring is struck. This double-throw reversing switch K is connected in a single series circuit with the motor in a well known manner. I have but briefly described the 45 construction of this switch arrangement, as of itself it forms no part of the present invention and is merely shown and described sufficiently to illustrate its application. Of course, as above indicated, any suitable 50 switching mechanism known to the art can be employed for this purpose.

By the arrangement shown herein, the varying and progressive tension applied to the 55 wire or metallic spring 4 will tune the latter up through a wide range or scale varying from a low pitch to a high pitch by a relatively slow movement during periods of one minute each for example, and if the membrane 2 to which such wire or string is attached, and which may be considered as in the nature of a sounding board, is struck by a submarine vibration of the same frequency as that corresponding to a tension 60 of the wire or string, or attuned thereto,

such wire or string will have a tendency to vibrate in unison with such submarine vibration, provided there be exercised upon the wire a transverse force, that is to say, a force tending to move the string transversely of its length. As shown in Fig. 1, this transverse force is obtained by placing the wire or string 4 in an air-gap 17 of a powerful electromagnet 18 and passing the electric current through the wire or string 75 by means of a suitable electric battery 19, in circuit with the former.

This of course, will tend to draw the wire or string out of the air-gap by the well known motor action. The reason for the 80 force that tends to draw the string of wire out of the air-gap lies in the fact that a circular magnetic field is set up exterior of the conductor, because of the passage of an electric current therethrough. This circular 85 electric field interferes with the electric field set up in the air-gap of the magnet. The lines of force of the field set up around the wire will be either clock-wise or counter clock-wise and accordingly will reinforce 90 the lines of magnetic force in the field of the magnet on either one side or the other. On the side upon which the reinforcing action occurs, there will be exerted a pressure tending to push the wire or conductor out of the 95 magnetic field. This constant transverse force acting upon the conductor causes the conductor to vibrate transversely rather than longitudinally on being set in vibration by the diaphragm.

100 I might here mention that this transverse force on the wire or string can also be obtained by the action of a magnet on a steel wire or string, as hereinafter described in connection with the modified form of the 105 invention shown in Fig. 4.

Referring again to Fig. 1 of the drawings, the electric circuit includes the battery 19, wire 19', the telephone transformer T with receiver R, wire 20', diaphragm 3, wire or string 4, block 5, and wire 5', and an electric current from the battery 19 is passed through the primary 20 of the telephone transformer T, whose secondary 21 is connected to the telephone receiver R. When 110 the string vibrates, ever so little, in the air-gap of the magnet, alternating electromotive forces, induced in the wire by such vibrations, will produce corresponding variations in the current passing through the 115 telephone transformer and the corresponding tone will be heard in the telephone receiver.

120 It is evident that by the continuous variations of the tension of the wire or string, the detector will sweep, so to say, the surrounding waters and will collect or detect any sounds or tones emitted in the water.

125 In employing the invention I may locate a set of the apparatus at each side of the 130

ship, as will be clearly understood by reference to Fig. 1, and by comparing the intensity of the sounds arriving at each of the corresponding telephone receivers, the approximate direction of the source of sound may be ascertained and determined, and this is of course a manifest advantage, especially when the vessel is navigating in dangerous or hostile waters.

10 In Fig. 2 I have shown a slightly modified form of the invention. In this instance, instead of passing the wire or string through a port or opening in the side of the vessel and fastening it to a diaphragm, I attach one end of the string as at 3' directly to the hull A' of the vessel and lead the string or wire through the air-gap 17' of the magnet 18' and apply the tension on the wire at stated periods in the same manner 20 as described for Fig. 1. This arrangement may be adopted in such instances where the plating of the vessel's hull is thin enough and of such material as to answer the purpose.

25 In Fig. 3 I have shown a further modified form of the invention, and in this instance the vibrations of the wire or string are not transmitted to the telephone receiver R by means of the induced alternating electromotive force, but by means of a microphone placed in circuit between the string or wire and the telephone receiver. The microphone effect is obtained by means of a slight electric contact taking place at 23 35 between the wire 4 and a thin platinum or carbon wire 24 resting lightly on the wire or string and in such manner as not to interfere with the vibrations of the latter. As the electric battery sends the current 40 through this contact and the telephone transformer T, the vibrations of the string will affect this current and be correspondingly heard in the telephone receiver.

45 In Fig. 4 I have shown another modification of the invention, also operating on the microphone principle, but with the difference that the transverse force on the wire or string is now exerted, not by electromotive means, but by a 50 purely magnetic device. The string in this instance is made of steel and over it is placed a magnet 25 which exerts a force or tension on the string tending to pull such string perpendicularly toward the poles of 55 the magnet as far as will be permitted by the length of the string.

60 Referring again to the form of the invention shown in Fig. 1, it is necessary that the electric circuit containing the wire or string, and the primary of the telephone transformer be of very low resistance, for the induced electromotive forces due to the vibrations of the string are very small and consequently can only produce appreciable 65 current variations if they work in a circuit of

very low resistance. It is for this reason that the battery in Fig. 1 should be preferably a thermo-cell battery, which as is well known, has both low resistance and low voltage. Such low voltage is an advantage 70 in this instance, as otherwise there would be a too heavy continuous current passing from the battery through the low resistance of the wire or string.

75 In the modification shown in Fig. 5 however, I have illustrated a preferable arrangement in the wiring, because it will permit the use of any ordinary battery cell.

In this form of the circuit a battery 22' is connected through a resistance 27 with 80 the conductor 4. In shunt with this circuit is the circuit containing the coil 20 of the primary of the telephone transformer. The resistance 27 is made either high or low depending upon the electro-motive force of 85 the battery 22' so that the exact, correct amount of electricity will flow through wire 4 and the shunt circuit containing the primary 20 of the telephone transformer to insure the maximum efficiency of operation. 90 The correct amount of resistance 27 to obtain the best result with each particular battery 22' may be determined by experiment.

95 In the circuit containing the cell I have also placed a reactance or choking coil 26, so that the induced electromotive force in the string 4 forces these current variations only and entirely into the circuit containing the primary of the telephone transformer. The current flows from battery 22' through 100 resistance 27, which as previously explained is suitably adjusted, through a reactance or choke coil 26, through wire 4, and likewise through the shunt circuit containing the primary 20 of the telephone transformer 105 and back to the battery. Upon wire 4 being set in vibration to cut the magnetic lines of force set up within the magnetic field as previously explained, an induced electromotive force will be set up in the wire 4. 110 This induced electro-motive force will be alternating in character because its value depends upon the speed with which the lines of magnetic force are cut by the wire and this, of course, depends upon the tone to 115 which the wire is adjusted. In other words, there is an alternating current corresponding to the period of vibration of the wire induced in the wire. This alternating current will be checked from flowing in the 120 circuit including the reactance coil 26 because of the great resistance that reactance coils have to alternating currents, but it will be allowed to flow unchecked through the shunt circuit containing the primary 20 of 125 the telephone transformer, and hence sounds will be produced in the telephone receiver R by reason of the connection between secondary 21 of the telephone transformer and the primary 20.

The operation of the apparatus shown in Fig. 5, is substantially the same as that of the apparatus illustrated in Fig. 1.

If desired the telephone receiver may be used in connection with the well known "audion amplifier" substantially as is done in wireless telegraphy, in order to amplify the produced electric current variations, before passing them through the telephone.

10 While I have herein shown the apparatus attached to the hull of the vessel, it will of course be understood that it may be otherwise associated or employed in connection with the latter.

15 What I claim is—

1. In a sound detector, a receiver, means for transmitting audible tones or sounds to the receiver, and means for automatically attuning the transmitting means in a range 20 or scale up and down between a relatively low pitch and a relatively high pitch.

2. In a sound detector, a receiver, and means for transmitting submarine tones or sounds to the receiver, said means including 25 a vibrating element, means for automatically increasing and decreasing the tension to said element, and means for exerting a transverse force on the element.

3. In a sound detector, a receiver, transmitting means for transmitting submarine tones or sounds to the receiver, including a vibrating wire, and means for automatically and progressively attuning the transmitting means whereby its pitch is successively 35 raised and lowered.

4. In a sound detector, a receiver and a transmitter, electric circuits in which both the receiver and transmitter are interposed, the transmitter circuit including a vibrating 40 wire under tension, and means for automatically increasing and decreasing the tension of the vibrating wire.

5. In a sound detector, a receiver and a transmitter, electric circuits in which both 45 the receiver and transmitter are interposed, the transmitter circuit including a vibrating wire under tension, and means, including an operating electric motor, for increasing and decreasing the tension of the vibrating 50 wire.

6. In a submarine sound detector, a receiver, a diaphragm transmitter, electric circuits in which both the receiver and transmitter are interposed, the transmitter circuit 55 including a vibrating wire under tension, means, including an operating electric motor, for increasing and decreasing the tension of the vibrating wire, and a magnetic device for applying a transverse force to the wire.

7. In a sound detector, a receiver, a sound transmitting diaphragm, electric circuits in which both the receiver and the transmitting diaphragm are interposed, the diaphragm 65 circuit including a vibrating wire under

tension, and means, including an operating electric motor, for automatically increasing and decreasing the tension of the vibrating wire.

8. In a submarine sound detecting apparatus, means for transmitting audible tones or sounds to the receiver, and electrically operated means for automatically attuning the transmitting means whereby the pitch of the tone may be varied up or down. 70

9. In a submarine sound detecting apparatus, a receiver, means for transmitting submarine sounds or tones to the receiver, said means including a vibrating element, means comprising a spring controlled weight 80 and a motor for operating the same for applying variable tension to said element, and means for exerting a transverse force on the element.

10. In a submarine sound detecting apparatus, a receiver, and means for transmitting submarine sounds or tones to the receiver, said means including a vibrating string or wire, a weight connected therewith, a spring exerting tension on said 90 weight, a slideable member connected with said spring, and a motor for imparting a sliding movement to said member, and means for exerting a transverse force on the element. 95

11. In a submarine sound detecting apparatus, a diaphragm, a string or wire connected at one end with said diaphragm, a sliding member resiliently connected with the other end of the wire adapted to tension the same, and a motor for periodically imparting movement to the sliding member. 100

12. In a submarine sound detecting apparatus, a diaphragm, a string or wire connected with said diaphragm, means for applying variable tension to said string or wire, and means for applying a transverse force to the string or wire, said latter means including a magnetic element located adjacent the string or wire and an electric battery in circuit with the string or wire and adapted to pass an electric current through the latter. 110

13. In a submarine sound detecting apparatus, a plate-like member forming a section of the hull of a vessel, a string or wire 115 connected with one end of said member, a resilient member connected with the opposite end of said string or wire, means operating on said resilient member to automatically apply variable tension to the wire, and means for exerting a transverse force on the wire.

14. In a submarine sound detecting apparatus, a plate-like member forming a section of the hull of a vessel, a string or wire 125 connected with one end of said member, a resilient member connected to the opposite end of said string or wire, means operating on said resilient member to automatically apply variable tension to the wire, a mag- 130

netic device for applying a transverse force to the wire, and a receiver located in an electric circuit with the wire.

15. In a sound detector, a transmitter automatically attuned to vary its pitch up and down between a relatively low and a relatively high pitch and a receiver.

In testimony whereof I affix my signature in the presence of two witnesses.
